Primary Examiner — Karen E Kearney*Assistant Examiner* — John M Otte(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my new design. The broken line showing of the remainder of the text, the icons, the graphical user interface, and the remainder of the display screen is for environmental purposes only and forms no part of the claimed design.
